Primary Examiner — Elizabeth Albert(74) *Attorney, Agent, or Firm* — Fay Sharpe LLP**CLAIM**

The ornamental design for a pen, as shown and described.

DESCRIPTION

FIG. 1 is a front view of a pen showing my new design;

FIG. 2 is a left side view thereof;

FIG. 3 is a rear view thereof;

FIG. 4 is a right side view thereof;

FIG. 5 is an enlarged top plan view thereof;

FIG. 6 is an enlarged bottom plan view thereof; and,

FIG. 7 is a perspective view thereof.

The broken lines in the drawings are included for the purpose of showing portions of the pen that form no part of the claimed design.

1 Claim, 6 Drawing Sheets(56)
